(57) **CLAIM**

The ornamental design for an apparatus for network cameras, as shown and described.

DESCRIPTION

FIG. 1 is a top, front and right perspective view of an apparatus for network cameras showing our new design; FIG. 2 is a bottom, rear and left side perspective view thereof;

FIG. 3 is a front elevational view thereof;

FIG. 4 is a left side elevational view thereof;

FIG. 5 is a bottom plan view thereof;

FIG. 6 is a top plan view thereof;

FIG. 7 is a rear elevational view thereof; and,

FIG. 8 is a right side elevational view thereof.

The portions of the article in broken lines are shown for illustrative purposes only and form no part of the claimed design.
